Primary Examiner — Richard Kearney*Assistant Examiner* — Benjamin M Weeks(74) *Attorney, Agent, or Firm* — Volpe Koenig(57) **CLAIM**

The ornamental design for a camera system component, as shown and described.

DESCRIPTION

FIG. 1 is a perspective view of a camera system component in accordance with our design;

FIG. 2 is a front elevational view thereof;

FIG. 3 is a top plan view thereof;

FIG. 4 is a left side elevational view thereof;

FIG. 5 is a rear elevational view thereof;

FIG. 6 is a right side elevational view thereof; and,

FIG. 7 is a bottom plan view thereof.

The broken lines represent portions of the camera system component in which the design is embodied that form no part of the claimed design.
